X-RAY APPARATUS AND METHOD FOR
CRYSTAL ANALYSIS

Herbert Friedman, Arlington, Va.

Application August 8, 1945, Serial No. 609,694

6 Claims. (Cl. 250—53)

(Granted under the act of March 3, 1883, as
amended April 30, 1928; 370 O. G. 757)

1

My invention relates to an apparatus and method for developing X-ray diffraction patterns of materials and particularly to an apparatus and method for the production of patterns of much improved intensity and definition.

In my prior Patent No. 2,386,785, filed July 28, 1942, I disclosed a method and apparatus for scanning rapidly the X-ray diffraction pattern of a material which method involves using a Geiger-Muller type of counter as the device for the detection of the separate lines of the pattern.

A general principle which it is desirable to follow in the production of X-ray diffraction patterns is to employ focused beams of substantially monochromatic X-rays in order to obtain intense patterns and sharp resolution of the lines constituting the pattern. Accordingly, it is an object of my invention to provide a specimen mounting device and holder for employment in a method of producing X-ray diffraction patterns of improved intensity and definition.

It is another object of my invention to provide a method of producing X-ray diffraction patterns of very sharp resolution using focused radiation in the practice thereof.

Other objects and advantages of my invention will in part be obvious and in part appear hereinafter in connection with the detailed description of the principle and several embodiments thereof taken in conjunction with the drawing of which:

Figure 1 represents a schematic diagram to show the geometrical relationship among the several parts of a spectrometer employed according to the principles of my invention;

Figure 2 is a horizontal sectional view of a series of specimen mounts to show the general form used to accomplish focusing in the development of a pattern;

Figure 3 is a side elevation of the holder for the specimen mount;

Figure 4 is a front end view of the apparatus shown in Figure 3;

Figure 5 is a sectional view of the apparatus shown in Figure 3 and is taken along the line 5—5 in Figure 3;

Figure 6 is a sectional view corresponding to that of Figure 5 of a modified form of the apparatus shown in Figure 5;

Figure 7 is an end view of the apparatus shown in Figure 5; and

Figure 8 is a sectional view taken along the line 8—8 of the apparatus shown in Figure 5.

In the development of a diffraction pattern, as stated, it is highly desirable that the X-ray

beam used to irradiate the material being studied be substantially monochromatic in order that the amount of background in the pattern be reduced to a minimum. Various means can be adopted for so doing, among which are the conventional devices of filtering the X-rays originating in the tube by directing the radiation through a metal screen having an atomic number lower than that of the anode metal of the tube, thereby filtering out all but the α radiation of the anode metal of the tube. In my copending application, Serial Number 609,695, filed of even date herewith, I have disclosed a method and a device for monochromating X-rays, without filtering, and simultaneously focusing the beam, which method comprises irradiating a focusing surface which has been coated with crystallites having strong selective reflectivity for a certain wavelength of radiation.

By observing the proposition that all angles inscribed in an arc of a circle are equal, it is possible to develop an X-ray diffraction pattern of a material in a manner such that the diffracted beams constituting lines of the pattern are focused sharply. The material to be studied is formed as a circular arc and is irradiated by a divergent beam from a point source of radiation lying on the circle which is an extension of the arcuate specimen. The focused diffracted beam forming the Bragg angle corresponding to the angle of irradiation is then found on the same circle at a point the same distance from the specimen as is the source of radiation. By providing for irradiation of the specimen from all angles in a quadrant, all diffracted beams in a quadrant can be detected at their respective focal points. These statements have referred to a point source of radiation, a specimen which is an arc of a circle, and a focal point of a diffracted beam, but it will be apparent from the discussion hereinafter that employment of a line source of radiation and a specimen which is a section of a cylinder will give a focused line of diffracted radiation. That is, discussion of the plane geometry of the method should not be considered as limiting the method for the plane merely represents a horizontal section through an apparatus employing the method.

Reference to the Bragg diffraction law

$$n\lambda = 2d \sin \theta$$

in which n is the order of the diffraction, λ the wavelength of the X-rays, d the atomic planar spacing, and θ the angle of diffraction, indicates that in order to develop a complete pattern, it is

necessary to irradiate the specimen at angles varying from zero through 90° in order to detect all the diffracted beams to be found in a single quadrant. Starting from θ equal to zero degrees it is apparent that rotation of a specimen about an axis lying in the surface of the specimen in a beam of radiation will develop its complete pattern. If the specimen be arcuate, focused diffracted beams will be found at appropriate points along a focusing circle as will be explained in greater detail in connection with Figure 1.

For a better understanding of the principle of my method of taking X-ray diffraction patterns and the construction and arrangement of the apparatus of my invention reference should be had to Figure 1 in which the geometrical relationship among the several parts of an X-ray spectrometer has been illustrated. In the drawing, 10 represents a point or line source of X-rays such as the anode 10a of an X-ray tube, 11 the beam originating at the anode and 12 a focusing monochromator, which is described in greater detail in my copending application, Serial Number 609,695. The focusing monochromator reflects the beam 13 therefrom and focuses it at 14. It is to be noted that these points, 10 and 14, lie on a circle 15, an arc of which is defined by monochromator 12. The focused beam 13 is substantially monochromatic and has its focal point at 14 whereas the beam originating at 10 contained all wave lengths of the X-ray spectrum of the anode metal of the tube.

Thus the point 14 can be treated as a point or line source of monochromatic X-rays. It should be understood that the monochromating of the X-ray spectrum is not indispensable to the production of a diffraction pattern. The method and apparatus indicated in the figure are merely illustrative of one way of monochromating an X-ray beam which makes possible the irradiation of a material with substantially monochromatic X-rays to produce a pattern having very little background. Actually, 14 may be considered to be a primary source of X-rays originating at an X-ray tube anode 10a.

Using 14, therefore, as an X-ray source, the divergence of the beam 15 can be controlled by passing it through a small slit 16 prior to permitting it to irradiate a specimen 17 which is mounted with an axis of rotation at 18 in a holder like that to be described in connection with Figures 3 through 8. The focused diffracted beam 19 is reflected from the specimen at a specific angle and the form of the specimen mount is such that it produces focusing of a diffracted beam for those certain angular positions corresponding to the points at which the diffracted beam forms the same angle with the specimen surface as does the axis of the primary beam. The diffracted beam will be focused at a point 21 on an arc of a circle 22 which has its radius equal to the X-ray source-to-specimen distance and its center at 18, the axis of rotation of the specimen.

It will be noted that in order for the diffracted beam 19 always to be focused substantially on the fixed circle 22, a variation in the curvature of the specimen mount 17 will be necessary for a condition necessary for focusing is that specimen 17 be of the same radius of curvature as the circle passing through 14, 18 and 21 designated the focusing circle. In the drawing, three positions of the specimen mount are indicated θ_1 , θ_2 , θ_3 . The first position θ_1 is that in which θ is substantially zero degrees and has the speci-

men mount substantially aligned with the axis of the beam 15. Accordingly, for a specimen having such angular relationship to the beam 15 to produce focusing of a diffracted beam on the fixed circle 22 it would be necessary for the specimen mount to have an infinite radius of curvature, or, in other words, to be a plane section like that shown in position θ_1 . After the specimen has been rotated to position θ_2 , a focused diffracted beam 19 for that Bragg angle is found at point 21 on the fixed circle, which point defines an angle twice the angle formed by the beam axis and the plane of the specimen. In order for the diffracted beam to be focused at 21 on the circle 22 when the specimen forms an angle θ_2 with the axis of beam 15, therefore, it is essential for the specimen to have a certain radius of curvature defined by the circle passing through points 14, 18 and 21.

Likewise, considering a further rotation of the position of the specimen in the development of its diffraction pattern, when the position reached is that indicated as θ_3 in the diagram of Figure 1, it appears that in order to produce the focusing of the diffracted beam 23 on the circle 22 at 24 it is necessary that the specimen have a different radius of curvature of the focusing surface to match the amount of rotation of the position of the specimen. To this end the specimen should have a curvature such that it forms an arc of a circle passing through points 14, 18, 24.

The geometry requires that the combinations of points 14, 18, 21 and 14, 18, 24, respectively, lie on circles. For convenience in taking a pattern, the position of the third point is varied through a quadrant defined by the spectrometer bracket 25. It is apparent, therefore, that an infinite number of circles could be drawn through the sets of points should a circle be drawn for each variation in the position of the third point. To arrive at a practicable solution, it is necessary only to provide specimen mounts adapted to focus rays on the circle 22 within a certain tolerance of error and the deviation of the locus of the focal points of diffracted beams from circle 22 is compensated by the aperture of detector 26. Accordingly, by providing a set of specimen mounts 17, shown in Figures 2, 2A, 2B, 2C and 2D, whose radii of curvature are varied over a range so that each specimen mount corresponds in curvature to the circle drawn through the three points, the source of the X-rays, the axis of rotation, and the focal point of the diffracted beam. The third point is made to take a series of positions along the arc 22 and the effect of substantially continuous variation of the radius of curvature of the specimen mount and continuous focusing of the diffracted beams along the arc 22 as a diffraction pattern is developed can be obtained with a minimum of error.

In Figure 2 there are shown three specimen mounts in section for employment in a diffraction apparatus in which the source-to-specimen and specimen-to-detector distances are equal to about 20 centimeters. In Figures 2 and 2A the face of the specimen mount and a vertical section thereof are shown. Figure 2 shows the face of the mount is depressed to define a specimen-receiving depression and the other figures indicate gradation in the radius of curvature. In the employment of specimens for making diffraction patterns according to this invention it is essential that the surface of the specimen being irradiated, which is a portion of a cylinder, contain the vertical axis of the specimen support as an ele-

ment thereof. This principle, and the structure for so maintaining the specimen during the taking of the pattern will be explained in more detail in conjunction with the description of the specimen holder.

Referring to Figure 3 which is a side elevation of an elementary specimen holding apparatus, 30 represents the vertical shaft of the holder having an axis of rotation 18. As pointed out in connection with Figures 1 and 2, it is essential that this axis of rotation of the specimen holder pass through the surface of the focusing specimen mount. In the drawing 32 represents a horizontal member which is cut to receive keyed holder 33 as shown in greater detail in adjacent Figure 4. Points 34, 35, and 36, 37 of the holder, which are the ends of lips 38 and 39 define fixed points on the circular arc of the specimen mount and it is desired that the arc defined by the curvature of the specimen mount not only pass through those two pairs of points but also that the height of the arc from the chords connecting the points be such that the axis 18 of the holder lie in the surface of the specimen, or form an element thereof. Accordingly, in the placing of a specimen mount in the holder, plunger 40 is provided in order to retain a specimen mount firmly and accurately within the holder in the position defined. Because the specimen mount will require a different radius of curvature for the different positions which it will assume in the development of a diffraction pattern by rotating it through 90°, a positioning device is provided in the form of a micrometer 41 for positioning a specimen mount to make the surface of the specimen include as an element the axis of rotation 18 of the holder.

Spring member 42 indicates a means for maintaining the support 33 for specimen mount 17 closely juxtaposed against the positioning element 41 to minimize error which might arise from its misalignment. Likewise spring member 42 and bearings 43 are provided in order to support plunger 40 in a horizontal position so that the thrust on the specimen mount will be horizontal. Member 44 provides a fixed point and support for 40 and 41. The details of the structure are shown in Figure 5 which constitutes a partial section of Figure 3 taken along line 5-5 shown in Figure 3.

Referring to Figure 5 there is illustrated, partly in section, the apparatus shown in Figure 3 where the several elements are identifiable by correspondence in numbers. In Figure 5 a specimen mount 17 has been shown in place and aligned correctly to have the surface 17a of the specimen mounted thereon coincide with the axis of rotation 18 of the holder. As will be noted the specimen mount or backing material urges the plunger 40 inwardly and accordingly the resultant force exerted by the spring 45 retains the arcuate specimen mount 17 closely within the defined area with the arc in contact with the two pairs of points 34-35 and 36-37. Horizontal adjustment of the position of the specimen mount can readily be made by means of positioning element 41 in order to place it in a position such that the axis of rotation 18 of the holder lies in the surface being irradiated as an element thereof.

When a set of specimen mounts of progressively varying curvature is employed, the measuring element can be calibrated directly in terms of the several specimen mounts. That is, the specimen mounts can be numbered to correspond to certain points on the scale in order that the position of the mount can be readily adjusted in the holder to maintain the loci of the focal points

of the focused diffracted beams on an arc corresponding to 22 in Figure 1.

In Figure 6 there is shown an apparatus in which the positioning element and the plunger are combined in the specimen holder to provide a unitary structure for positioning the specimen mount. In the drawing, 60 represents the positioning element and 61 the mount or support therefor which holds it in a fixed position on the horizontal member 32. The measuring or the moving barrel portion of the positioning element is represented by 62 which is partially in section in order to show the interior structure thereof which permits the mounting of a plunger 40 therein. The plunger 40 is fitted within the barrel 62 by means of sleeve 63 and bushings 64 and 65. The spring member 66 retained in position coaxially with the plunger is shown as abutting against interior bushing 64 in the barrel. The specimen mount 17 is shown in position with the material constituting the specimen to be examined placed so that the axis of rotation 18 of the mount passes through the surface 17a thereof. When in such a position, it is noted that the plunger 40 is forced back and the spring 66 is compressed whereby the specimen mount 17 is positively urged forward to engage closely the points 34, 35 and 36, 37 in order that the specimen mount itself will coincide exactly with an arc of the circle defined by the source of X-rays, the axis of rotation of the mount, and the focal point of the diffracted ray.

In Figures 7 and 8 there are shown an end view and top elevational section, respectively, of the holder and specimen mount in position as shown in Figures 5 and 6. It will be seen that the operation of the device is such that the specimen mount is always urged into contact with the two pairs of points 34-35 and 36-37 on the specimen retainer 33 which points in turn are placed on the defined circle by adjustment of the height of the arc defined by the arcuate specimen mount itself. In this manner, focusing of the diffracted beam along a given fixed circle 22 (Figure 1) defined by the spectrometer bracket and the locus of the detector 26 is consistently accomplished.

Consideration of the geometry of the spectrometer table top and the relationship of the parts will indicate clearly that the radius of the circle defined by the point source of X-rays, the axis of rotation of the mount, and the focal point of the diffracted beam does not remain constant but that, as the specimen is rotated about axis 18, the radius of curvature diminishes from an infinite value when θ is zero degrees to a minimum value when θ is 90°. Accordingly, allowance must be made therefor in the development of a diffraction pattern in order that serious error will not be made in detecting the focused diffracted beam by scanning a quadrant defined by the spectrometer bracket 25. If the dimensions of the apparatus be made large and the width of the specimen be made small it can be shown mathematically that the specimen will at no time deviate seriously from a short arc, so that, by proper placing of the detector, substantially focused diffracted beams will be detected by moving the detector through the arc defined by the bracket of the spectrometer. However, in precision work, such a compromise is impracticable and some reasonable approach to continuous variation of the radius of curvature of the specimen mounts to correspond to the radius of curvature of the circle is necessary in order that fine definition of the lines of the pattern be made. This be-

comes particularly necessary when it is desired to bring out the more obscure lines of a pattern. By using a specimen having a large area and a series of specimen mounts like those shown in Figure 2, each having the same total area as the other but each having a slightly different radius of curvature to correspond to a series of positions throughout the range of positions taken by the mount in the development of a diffraction pattern, a very intense pattern can be developed in which even the minor lines are brought out sharply by virtue of the combination of irradiating the large area and focusing the beam diffracted therefrom.

Referring to Figure 1 where the geometric relationship of the elements of an X-ray spectrometer has been shown, it will be apparent that in the rotation of a specimen through 90° to develop its diffraction pattern, changes in its radius of curvature are necessary. For maintenance of perfect precision and keeping the focal point of a diffracted beam on the circle 22 a continuous change in the radius of curvature of the specimen holder to correspond exactly to that of the circle defined by the points 14, 18 and a point on the quadrant 22 would be necessary. A practicable compromise of the difficulty of providing for continuous change of the radius of curvature of the mount is adopted by providing a series of specimen mounts having different radii of curvature to be used in a series of progressive positions through the series taken by the specimen as it is rotated to develop its diffraction pattern. By placement of the diffracted beam detector close to the circle 22 and adjustment of the radii of curvature of the several specimen mounts so that the focal point of the diffracted beam does not deviate farther from the focusing circle 22 than the location of the entrance to the diffracted beam detector, a close approximation to continuous variation of the radius of curvature of the specimen can be made. It is readily shown that by providing a series of curved specimen mounts to correspond to 5° rotations of the specimen in the development of a diffraction pattern, errors in the deviation of the focal point of the diffracted beam from the circle 22 will not exceed 1%. In this manner, the most complex diffraction pattern having very obscure fine lines can be readily scanned and the lines detected relatively easily with a fine degree of definition. An advantage accrues from the use of a relatively large specimen such as shown in Figure 2 for by the irradiation of a large area a more intense line is reflected therefrom and focused on the focusing circle.

The details of the construction of the detector found most useful for scanning the pattern are given in my prior Patent No. 2,386,785. The detector comprises a Geiger Muller type of counter which is made specifically sensitive to the radiation being used to develop the pattern and can be rendered substantially 100 per cent efficient in its counting action.

The preparation of the specimen for irradiation is relatively simple. It is used in finely divided form, made into a thick paste with water or a non-crystalline binding agent and coated evenly into the depression formed into the specimen mount. Binding agents such as methyl cellulose, collodion, styrene solutions, or polyvinyl alcohol are useful for the purpose.

Since certain changes in carrying out the above method and in the construction of the apparatus described, which changes embody the invention,

can be made without departing from the scope of the invention, it is intended that all matter contained in the above description or shown in the accompanying drawings shall be interpreted as illustrative and not in a limiting sense.

The invention described herein may be manufactured and used by or for the Government of the United States of America for governmental purposes without the payment of any royalties thereon or therefor.

Having described my invention, what I claim as new and desire to secure by Letters Patent of the United States is:

1. The method of developing an X-ray diffraction pattern of a substance comprising, coating an arcuate mount with a sample of the substance, defining an element of the arcuate surface of said mount as an axis of rotation for said mount, irradiating the material coated on said mount with X-rays, detecting diffracted rays at a focal point on a focusing circle defined by the source of the X-rays, the axis of rotation of the specimen, and the focal point of the diffracted beam being measured, and during rotation of the mount maintaining the focal points of diffracted beams being measured substantially on a common arc by substituting different arcuate mounts having different curvatures on which the material being examined is coated.

2. The method of developing an X-ray diffraction pattern of a substance comprising, irradiating the concave surface of a specimen thereof which is a section of a cylinder to produce a beam of radiation, rotating said specimen through substantially 90° about an axis forming an element of said cylindrical irradiated surface to develop a diffraction pattern thereof, synchronously moving with said specimen a detector to detect the focused diffracted beam corresponding to the angle of incidence of the radiation on an arc having as its center the axis of rotation of the specimen, and repeating the above steps with an arcuate mount having a different curvature to maintain the locus of the focal point of the diffracted beam on an arc substantially concentric with the arc traversed by the detector.

3. The method of developing the X-ray diffraction pattern of a material comprising, coating a curved focusing surface of a mount with a sample of the material, irradiating the surface of said material with a divergent beam of X-rays from a point source, detecting the focused diffracted rays on an arc of a focusing circle defined by the source of the rays, the axis of rotation of the specimen, and the focal point of said diffracted beam, and maintaining the locus of the focal points of the diffracted beams substantially along an arc by substituting coated mounts of different curvature for the different angular positions.

4. The method of developing an X-ray diffraction pattern of a material comprising, irradiating a specimen thereof having a surface curvature formed to produce a focused diffracted beam of radiation at an angle corresponding to the angle of the irradiating beam, rotating said specimen substantially 90° about an axis lying in its focusing surface to develop a diffraction pattern thereof, synchronously moving with said specimen a detector to detect the focused diffracted beams along an arc having as its center the axis of rotation of the specimen, and substituting specimens of the same material but of different curvature to maintain the locus of the focal points of the focused diffracted beam substan-

tially concentric with the arc traversed by the detector.

5. In an X-ray spectrometer for developing X-ray diffraction patterns of materials by rotating an arcuate specimen of a material through an angle about an axis to maintain the focal point of the diffracted beam of X-rays on an arc of a circle having as its center the axis of rotation of the specimen, apparatus for maintaining the specimen in focusing relation to the incident radiation and allowing for change of its radius of curvature to correspond to different degrees of rotation thereof comprising, a holder to receive the arcuate specimen and to define a chord of the focusing circle, means for holding the arcuate specimen in fixed position in said holder, and means for adjusting the horizontal position of the arcuate specimen holder to make the axis of rotation of the holder lie in the surface of the specimen.

6. Apparatus for the development of an X-ray diffraction pattern of specimens, comprising, a fixed point source of X-ray radiation, a detector

of diffracted radiation movable along a fixed curved track, fixed holding means for said specimens disposed substantially in the plane of said source and said fixed track, and a series of specimens with their surfaces curved in one dimension and with varying radii of curvature, the curvature of a particular member of said series when said member is disposed in said holder defining an arc of a circle on which lie said point source of radiation and said detector, the particular position of said detector on its track corresponding to the curvature of said particular member.
